UNITED STATES PATENT OFFICE.

ALLAN C. RUSH, OF LOS ANGELES, CALIFORNIA.

INJECTOR-BURNER.

No. 797,230.

Specification of Letters Patent.

Patented Aug. 15, 1905.

Application filed August 25, 1904. Serial No. 222,095.

To all whom it may concern:

Be it known that I, ALLAN C. RUSH, a citizen of the United States, residing in the city of Los Angeles, in the county of Los Angeles and State of California, have invented certain new and useful Improvements in Injector-Burners, of which the following is a specification.

This invention relates to positive and efficient means for utilizing liquid hydrocarbon as fuel, and particularly to means for thoroughly and completely atomizing said fuel.

The primary object of the invention is to provide an injector-burner which while extremely useful shall be very positive and efficient in operation and in which all liability of clogging or choking the burner by carbonization will be avoided and which shall be simple and cheap in construction and which shall be peculiarly adapted for use with heavy crude hydrocarbon oils—such as, for instance, the heavy crude asphaltum oils of California.

To this end the invention consists in the constructions and combinations of parts hereinafter described in detail, but particularly pointed out in the claims.

The invention will be more readily understood by reference to the accompanying drawings, forming a part of this specification, and in which—

Figure 1 is a plan view of a burner embodying my invention, the cap of the burner having been removed. Fig. 2 is a longitudinal sectional view of the line X² X² of Fig. 1. Fig. 3 is an inverted plan view of the cap of the burner of the style shown in Fig. 2. Fig. 4 is a side elevation of a burner embodying my invention, showing another means of retaining the cap or cover in position. Fig. 5 is an inverted plan view of a modified form of the cap or cover.

As shown in the drawings, the casing 2 is provided with a chamber 3, and through the center of this chamber extends a pipe or cylindrical casing 4, which may be integral with the casing 2, as shown in the drawings, or may be removably secured therein. The rear end of the casing 2 is open to receive the oil-pipe 5, and the steam-pipe 6 extends through the pipe 5 into connection with the casing or pipe 4, the pipes 6 and 4 forming the steamway. The casing 2 at its upper or outer end is closed by a suitable top 7, and this top or floor 7 is provided at its center with an opening 8, registering with the way 4' of the casing or pipe 4. The opening 8 is

preferably flared outwardly toward its top, as shown, to provide for the expansion of the steam. An annular channel 9 is provided on the top plate 7, as shown, and at the front of the casing 2 this channel extends clear through the top plate 7 and into communication with the oil chamber or way 3, and forms the oil-outlet 10.

11 represents a spacer-plate adapted to be secured on the top plate 7 and provided with a cut-away portion, so that the plate 11 forms, in effect, a segmental ring. The segmental ring 11 is so positioned on the top plate 7 that this cut-away portion is toward the open oil-duct 10.

The casing 2 is provided at its upper end with an annular flange 12, which is flat on its upper face and extends out beyond the annular channel 9. This flange 12 terminates below the level of the upper surface of the top plate 7, so that the upper face of the flange 12 is slightly lower than the upper face of the plate 7.

13 represents a member adapted to fit upon the upper end or top of the casing 2. This member 13 is provided with an annular flange 14, corresponding to the flange 12 of the casing 2 and adapted to rest thereon. The flanges 12 and 14 are provided with suitable holes through which bolts 15 are adapted to be inserted to hold the member 13 rigidly in place with respect to casing 2. The member 13 is provided with a bead 16, adapted to rest in the annular channel 9.

By reference to Fig. 3 it is seen that both flange 14 and bead 16 of the member 13 are cut away at the front of the burner and over the annular oil-outlet 10, and that the member 13 thus forms, in effect, a segmental ring, the cut-away segment of which controls the width of the flame from the burner, and that said cut-away portions substantially correspond to the cut-away portions of the burner-plate 11.

17 represents the cap or cover proper and is threaded, as shown at 18, to engage the correspondingly-threaded portions 19 of the member 13. This cap 17 is provided with an annular flange 20 above the threaded portion 18, which prevents the cap being turned down into the member 13 more than a certain distance. The head of this cap is either squared or formed with six sides for the application of a wrench, by which the cap may be screwed into place. The under surface of this cap is concave, as shown at 21, so that when the cap

17 is in place over the steamway 4' an expansion-chamber is formed thereby. The use of the spacer-plate 11 permits the cap 17 to be screwed down tight onto said spacer-plate and the cut-away portion of the spacer-plate insures the formation of the steam-discharge slot 22 of the requisite vertical width. It is obvious, however, that if it is desired to increase the width of this steam-discharge slot the same may be readily accomplished by a partial turn of the cap 17.

23 represents the partition in the center of the oil-discharge slot 10. This partition may be extended down into the oil way or chamber 3 or may be terminated slightly below the surface of the discharge-slot 10.

In Fig. 4 I have shown a slightly-modified form of my invention. In this modification I have shown the cap 17' held in place on the top of the casing 2 by means independent of the cap. This means consists in providing a cap-holding arm 23, provided at its forward end with a head 24, the under surface of which is adapted to rest on the top of the cap. This arm 23 is provided toward its rear end with side lugs 25, and the pipe 5 is provided with lugs 26, which extend up above the arm 23 and are provided with undercut recesses 27, in which the lugs 25 are adapted to rest. The arm 23 is provided at its rear end with a threaded hole, and in this hole a bolt 28 is adapted to work. By adjusting the bolt 28 the arm 23 may be caused to hold the cap 17' forcibly in place on top of the casing 2 or to release same, as may be required.

The cap 17' of Figs. 4 and 5 is substantially the union of the member 13 and the cap 17 and is provided with a flange 14', corresponding to flange 14, and with a bead 16', corresponding to the bead 16, and with a cut-away portion corresponding to the cut-away portion of Figs. 2 and 3. In Fig. 5, however, I have shown the spacer-plate 11' as attached to the under side of the cap 17' and the center of the under side of said cap concave at 21', so as to form an expansion-chamber for the steam. It will be noted, Figs. 3 and 5, that the bead 16 of the member 13 extends beyond the edges of the cut-away portion. By thus extending the ends of the segmental ring the upward and outward flow of oil through the oil duct or outlet 10 is so regulated that oil is only permitted to flow out from the oil-duct at a point away from the edges of the cut-away portion, and as the steam-discharge slot 22 is of the same width as the cut-away portion it is obvious that any possibility of the oil flowing up over the edges of the cut-away portion is avoided and any possibility of carbonization on the cut-away is absolutely eliminated.

The operation of the burner is as follows: The pipe 6 is connected with a suitable steam-supply, and pipe 5 connected with a suitable oil-supply, the oil being under slight pressure.

The steam passing through the steam-duct 4' and into the expansion-chamber formed above the opening 8 is evenly supplied to the steam-outlet 22 and flows over the face of the top plate and out over the oil-outlet 10 and draws the oil from the outlet 10 up into the steam, as the face of the flange 12 is somewhat lower than the face of the top plate 7. The object of the partition 23 is to prevent the oil all running to one side of the slot 10 when the burner is tipped from a horizontal position—as, for instance, when a locomotive is rounding a curve or when the burner is used on a ship and the ship is pitching with the sea.

Having now particularly described my invention, what I claim as new, and desire to secure by Letters Patent of the United States, is—

1. A hydrocarbon-burner comprising a body having a central steamway, and an oilway surrounding the same, said oilway having a closed top, provided with a curved or arc-shaped upwardly-opening oil-outlet near the rim of said body, a segmental spacer-plate mounted upon said body and surrounding the outlet from the steamway, a cap-retaining member provided on said body, said cap-retaining member provided with a cut-away portion corresponding to the cut-away portion of said segmental spacer-plate, the cap or cover held in position on said body by said member, the under side of said cap or cover provided with a concavity forming an expansion-chamber above said steamway, and said cap or cover providing a steam-discharge slot adapted to discharge steam across said upwardly-opening oil-outlet.

2. In a hydrocarbon-burner comprising a body having a central steamway and an oilway surrounding the same, said oilway having a closed top provided with a curved or arc-shaped upwardly-opening outlet near the rim of said body, a cap over said body, said cap being circular in cross-section and having the under side concave to form a steam-expansion chamber above said steamway, and forming with the closed top of said oilway a steam-discharge slot, discharging across the plane of said oil-outlet, and means for holding said cap in place on said body.

3. A hydrocarbon-burner comprising a body having a closed top provided at its center with an opening communicating into a central steamway, and with a curved or arc-shaped opening near the rim of said body opening into the chamber surrounding said steamway, means for supplying steam and oil to said steam and oil ways, respectively, the upper face of said body provided with an annular channel, the cap or cover provided with a bead adapted to fit in said channel, means for holding said cap or cover on said body, said cap or cover having a concave under side forming a steam-expansion chamber above said steamway, a segment of said cap and of the bead

thereof being cut away to form a steam-discharge slot behind said curved opening whereby the steam is discharged across the plane of said opening.

4. A burner comprising a body, having steam and oil ways, the oilway terminating in a peripheral upwardly-opening curved or arch-shaped outlet at the rim of said body, a cap mounted on said body above the termination of the steamway, said cap having a concave under side, a spacer-plate between said cap and the upper surface of said body, said spacer-plate and said cap being cut away opposite said oil-outlet, forming a steam-discharge slot adapted to direct steam out across the plane of the opening of said oil-outlet.

5. A hydrocarbon-burner, comprising a body having a steamway and an oilway and a closed top, the oilway terminating in an arc-shaped upwardly-opening oil-outlet at the rim of said body, the steamway opening upwardly through the center of the top of said body, a cap-retaining member provided on said body, the top of said body provided with an annular channel, said retaining member provided with a bead adapted to fit in said channel, a cap or cover, said cap or cover provided with a concave under face forming a steam-expansion

chamber above said steamway, said cap and retaining member having cut-away portions forming a steam-discharge slot opposite said oil-outlet and above the same.

6. A hydrocarbon-burner comprising a body having a central steamway and an oilway surrounding said steamway, said oilway being closed at its top, and provided with curved or arch-shaped upwardly-opening oil-outlet near the rim of said body, a cap or cover for said steamway, a steam-expansion chamber being provided under said cap or cover, said cap or cover provided with a cut-away portion adapted to form a steam-discharge slot, discharging across the plane of said oil-outlet, a segmental bead adapted to close a portion of said oil-outlet, the ends of said segmental bead extending beyond the edges of said cut-away portion and means for holding said cap or cover in position on said body.

In testimony whereof I have hereunto set my hand, at Los Angeles, California, this 18th day of August, 1904.

ALLAN C. RUSH.

In presence of—

FREDERICK A. LYON,
RILLA ROBERTS.
